UNITED STATES PATENT OFFICE.

ROBERT TAPPAN, OF NEW YORK, N. Y.

CHANGE-RECEPTACLE.

1,242,739.

Specification of Letters Patent.

Patented Oct. 9, 1917.

Application filed March 8, 1916. Serial No. 82,830.

To all whom it may concern:

Be it known that I, ROBERT TAPPAN, a citizen of the United States, residing at New York, in the county of New York and State of New York, have invented certain new and useful Improvements in Change-Receptacles, of which the following is a specification.

The present invention relates to coin handling devices and more particularly to change receptacles.

An object of my invention is to provide a change receiving and delivering device into which coins may be placed when handing change over a counter to a customer, it being the usual practice at the present time to place the change on the counter rendering it extremely difficult at times for the customer to pick up the same particularly with a gloved hand. My invention contemplates the provision of a receptacle into which the change may be deposited, said receptacle having a depressible platform therein which receives the coins and down which the coins slide into the hand of the person for whom they are intended.

Another object of my invention is to provide a device of the class described, which is simple in construction, cheap to manufacture, strong and durable and effective in operation.

Other objects and advantages to be derived from the use of my invention will appear from the following detail description and the claim, taken with an inspection of the accompanying drawing, in which—

Figure 1 is a perspective view of a change receiving device embodying the improvement of my invention,

Fig. 2 is a top plan view of the same, a portion thereof being broken away, and

Fig. 3 is a longitudinal sectional view taken on the line 3—3 of Fig. 2.

Referring more particularly to the drawing, in which similar characters of reference designate like and corresponding parts throughout the various views, 1 designates the body of my improved change receptacle, said body being preferably elliptical in configuration and having a base wall 2. The receptacle is provided with a top wall 3 extending approximately one-third or one-half the length of the receptacle to form an open-

ing 4. At the forward end of the receptacle 1 the peripheral wall thereof is provided with an outlet aperture 5 for a purpose which will hereinafter appear.

I provide coin receiving and delivering means which comprises preferably a platform 6 hingedly mounted on a transversely extending rod 7 carried in the receptacle 1 adjacent the terminating point of the wall 3. The platform 6 is provided with extensions 8 which are rolled about the rod 7 and a coil spring 9 is interposed between said extensions 8 and about said rod, the free ends of said coil spring engaging, respectively, the under surface of the wall 3 and the platform 6. The free end of the platform 6 is provided with an arm 10 extending through the opening 5 for a purpose which will hereinafter appear. From the arrangement thus provided it will be seen that the platform 6 is maintained normally in a position adjacent the upper edge 70 of the opening 5, said platform preferably being inclined toward the front end.

In use the coins are deposited by the clerk in the receptacle 1 on the platform 6, and the customer depresses the platform by placing the back of his hand on the arm 10, thereby causing the coins to slide through the opening 5 into the palm of his hand. From the above it will be seen that I have provided a coin receptacle which facilitates the handling of money and the construction of the device permits its movement from place to place on a counter.

From the above description taken in connection with the accompanying drawings, it is thought that a clear and comprehensive understanding of the construction, operation and advantages of my invention may be had, and while I have shown and described my invention as embodying a specific structure, I desire that it be understood that I may make such changes on said structure as do not depart from the spirit and scope of the invention as claimed.

What I claim as new and desire to secure by Letters-Patent is:—

A device of the character described the combination of a receptacle comprising a base, a body portion formed on said base, one end of the body being provided with an opening, a top wall provided with an open-

ing, a rod extending transversely of the opening and mounted in said body adjacent the top wall, a platform, extensions formed on one end of the platform, said extensions being rolled about the rod providing means for hingedly connecting the platform to the rod, a coiled spring mounted on the rod be-

tween the extensions adapted to normally retain the platform in raised position, and an extension formed on said platform projecting through the opening in the body for a purpose specified. 13

In testimony whereof I affix my signature.
ROBERT TAPPAN.
